UNITED STATES PATENT OFFICE.

ALBERT J. CHAMPION, OF FLINT, MICHIGAN, ASSIGNOR TO CHAMPION IGNITION COMPANY, OF FLINT, MICHIGAN, A CORPORATION OF MICHIGAN.

SPARK-PLUG.

1,263,038.

Specification of Letters Patent. Patented Apr. 16, 1918.

Application filed June 4, 1917. Serial No. 172,661.

To all whom it may concern:

Be it known that I, ALBERT J. CHAMPION, a citizen of the Republic of France, residing at Flint, in the county of Genesee and State of Michigan, have invented certain new and useful Improvements in Spark-Plugs, of which the following is a specification, reference being had therein to the accompanying drawings.

10 The invention relates to spark-plugs and has more particular reference to the construction of the insulator and coöperating electrode as hereinafter set forth.

In the drawing:

15 Figure 1 is a longitudinal section through an insulator of my improved construction, showing the electrode in engagement therewith;

20 Figs. 2, 3 and 4 are cross-sections in planes 2—2, 3—3 and 4—4 respectively.

In the construction of spark-plugs which are designed for use with high-speed engines or in other places where subjected to intense heat, it is very essential to provide 25 adequate means for dissipating the heat from the insulator and electrode passing therethrough, the electrode being made of metal having a high rate of thermal conductivity, and it is desirable to restrict the 30 area which is exposed to the combustion heat. On the other hand, this electrode itself forms a means for dissipating the heat which is imparted to the insulator, and for this purpose a large cross-section is ad- 35 vantageous. I have therefore devised a construction of electrode and coöperating insulator in which the inner or exposed end of the electrode is of relatively small cross-section, and the cross-section of the out- 40 wardly-extending shank portion is progressively increased. The insulator is correspondingly fashioned, being provided with a small bore at its inner end for receiving the small end of the electrode and a series of

enlarged bores or counter-bores for receiving the corresponding portions of the electrode.

In detail, A is an insulator formed of any suitable material and adapted for mounting in a metallic casing of any suitable construction (not shown). This insulator is formed with a small bore B at its inner end, which extends through the inwardly-projecting portion C thereof in the central or body portion D of the insulator, which is of larger 50 diameter and is subjected to the clamping stresses of the casing. The bore E is of increased diameter, while the outwardly-projecting portion F of the insulator has a still larger bore G. The electrode H is provided with portions I, J and K for respectively fitting in the bores B, E and G.

With the construction described, when the spark-plug is in use and subjected to high heat, the small section I of the electrode will 65 restrict the amount of heat conducted therethrough, while the successively larger cross-sections of the electrode are useful in more rapidly dissipating heat from both the exposed portion of the electrode and from the 70 insulator itself. The advantage of having a series of steps instead of a single enlargement is that the insulator is stronger mechanically and is also subjected to more gradual temperature changes, which lessen 75 the tendency to fracture.

What I claim as my invention is:

In a spark-plug, the combination of an insulator having a small sized bore through the inwardly-projecting portion thereof, an 80 enlarged bore through the enlarged central or body portion and a further enlarged bore through the outwardly-extending portion, and an electrode having portions of corresponding size for fitting within said 85 insulator.

In testimony whereof I affix my signature.

ALBERT J. CHAMPION.
